UNITED STATES PATENT OFFICE.

ALFRED KÄSTNER AND KARL STRATOMEYER, OF ESSEN, GERMANY, ASSIGNEES TO
FRIED. KRUPP AKTIENGESELLSCHAFT, OF ESSEN-ON-THE-RUHR, GERMANY.

FOUNDATION FOR GUNS.

1,385,136.

Specification of Letters Patent. Patented July 19, 1921.

Application filed September 4, 1920. Serial No. 408,389.

To all whom it may concern:

Be it known that we, ALFRED KÄSTNER, residing at Essen, Germany, and KARL STRATOMEYER, residing at Essen, Germany, both citizens of the Republic of Germany, have invented a certain new and useful Improvement in Foundations for Guns, (for which we have filed application in Germany, filed August 8, 1917,) of which the following is a specification.

The present invention refers to a foundation for guns, which in addition to being of simple construction is distinguished by great strength and resistance.

The invention will be described with reference to the accompanying drawings, which show the invention applied to guns with wheeled gun carriages.

Figure 1 is a side elevation of the foundation,

Fig. 2 is the corresponding plan view,

Fig. 3 is a section on the line 3—3 of Fig. 2,

Fig. 4 is a section on the line 4—4 of Fig. 1,

Fig. 5 is on a larger scale a section on the line 5—5 of Fig. 3,

Fig. 6 is a plan view of parts of the foundation,

Figs. 7 to 10 are vertical longitudinal sections of the inner ends of the parts shown in Fig. 6.

The body of the foundation consists of four parts (A, B, C, D), which are of rectangular cross section (see particularly Fig. 4) and are built up of plates and angle irons and riveted together and therefore constructed like box girders. These parts are intended to form a rigid cruciform body, which is let into the ground. Each of the parts A, B, C, D carries on the end, which is located inward when the foundation is put together, two lugs a^1 a^2 b^1 b^2 , c^1 c^2 , d^1 d^2 , respectively (see particularly Figs. 7 to 10) which project beyond the inner end of the parts A, B, C, D. One lug is attached to the cover plate and the other lug to the base plate of the box and either directly to the under or upper side of the base and cover plate (see Figs. 8 and 9) or by the aid of an intermediate piece (a^3 , a^4 , d^3 d^4) to the upper or under side of these plates (see Figs. 7 and 10). In consequence of this arrangement these lugs can engage with each other by their inner ends in the manner

shown in Fig. 3, when the parts A, B, C, D are at the same level or height. Each of the lugs is provided at the end, which projects beyond the parts A, B, C, D with a circular through aperture a^5 a^6 b^5 b^6 c^5 c^6 d^5 d^6 , respectively (see Figs. 6 to 10.) Into the openings a^5 are inserted sleeves E, F, which are rigidly connected to the lugs. These sleeves, the one of which is connected to the lower lug (a^2) and is closed at the bottom, serve to receive a pin G (see Figs. 1 to 3 and 5), which is adapted to bear with a collar g^1 (see Fig. 3) against the upper edge of the sleeve F and can be connected thereto by a bayonet joint f^1 f^2 g^2 (see Figs. 3 and 5). A bolt J adapted to be inserted in through apertures in the sleeve E and the pin G after this bayonet joint has been connected up (see Figs. 1 and 3), serves to prevent the pin G from being turned around in the sleeves E F.

When assembling the foundation, the part A is first laid out and then the part B, next the part C and finally the part D placed up to the part A so that the parts form a cross and the lugs b^1 c^1 d^1 engage with their apertures b^5 c^5 d^5 over the sleeve E and the lugs b^2 c^2 d^2 with their openings b^6 c^6 d^6 over the sleeve F. The pin G is then inserted in the sleeves E F and locked to the sleeves by means of the bayonet joint f^1 f^2 g^2 and the bolt J.

In order to stiffen the parts A, B, C, D relatively to each other substantially channel shaped pieces a^7 b^7 , c^7 , d^7 (see Figs. 1, 2 and 6) are fixed to the side wall of these parts at right angles thereto and into them can be pushed struts H from above. The struts H are I-shaped in cross section and are adapted to rest on the angle irons a^8 , b^8 c^8 d^8 , which are attached to the pieces a^7 b^7 c^7 d^7 and carry pins and screws (see Fig. 1) for the purpose of connecting them to the struts H. These struts, which serve as a track for the wheels of the gun carriage and a roller m^1 (see Figs. 1 and 2) project above the cover plates of the boxes A, B, C, D a short distance. In order to compensate this difference in height, that is to say, in order to provide a perfectly level track for the wheels of the gun carriage and the roller m^1 plates a^9 b^9 c^9 d^9 are attached to the cover plates of the boxes A, B, C, D respectively.

The roller m^1 is carried on a bearer M (see Figs. 1 and 2) for the trail of the gun car-

100

110

riage, which can be swung about the pin G (pivot pin) and which rests with its rear end (not shown in the drawing) on the ground.

5 Owing to its shape the foundation let into the ground has in addition to requiring a comparatively small amount of constructional material, great power of resistance, as the recoil of the gun no matter whether it 10 takes place in the longitudinal direction of the supports of the foundation or at an incline to this direction, is transmitted by the high and long side walls of the carrier to a very considerable ground area. The foundation therefore requires no anchoring by 15 means of spikes, spades or the like.

Claims.

1. A foundation for guns comprising box-shaped girders disposed in the shape of a 20 cross, superposed lugs projecting from the inner ends of the girders and provided with registering apertures, alining sleeves passing through said apertures, a pin adapted to pass through said alining sleeves to removably lock together the girders, I-shaped struts secured to the sides of said girders and disposed therebetween for bracing the same, said I-beams having their upper faces positioned so as to form a track surface substantially concentric with said locking pin. 25

30 2. A foundation for guns which comprises girders disposed in the form of a cross, said girders being box-shaped in cross sections,

means for detachably uniting said girders, and means disposed between said girders and 35 forming a track surface, for bracing the same and retaining them in their proper positions.

3. A device of the class described which comprises girders arranged in the shape of 40 a cross, superposed lugs secured to the inner ends of said girders, said lugs being provided with registering apertures, alining sleeves passing through said apertures and a pin passing through both sleeves and 45 removably secured in place, substantially as described.

4. A device of the class described which comprises girders disposed at right angles to one another in the shape of a cross, means 50 for uniting the girders at their inner ends, a bracing means disposed between the several girders which comprises channel-shaped pieces secured to the sides of the girders and struts which are I-shaped in cross section 55 mounted in said channel-shaped pieces and having their upper face adjacent the top sides of said girders, as and for the purpose set forth.

The foregoing specification signed at 60 Essen, Germany, this 11th day of June, 1920.

ALFRED KÄSTNER.
KARL STRATOMEYER.

In presence of—

HANS GOTTMANN,
JOSEF ALBERTZ.
